SHOE FILLING MACHINE

William Neil Bray and Charles Martin Bagshaw,
Leicester, England, assignors to United Shoe
Machinery Corporation, Borough of Flemington,
N. J., a corporation of New Jersey

Application August 13, 1940, Serial No. 352,438
In Great Britain August 24, 1939

8 Claims. (Cl. 12—79.6)

This invention relates to machines for filling the cavities in the bottoms of shoes, for example, the cavities which lie within the inseam in the forepart or the forepart and shank of Goodyear welt shoes.

After such a shoe has been lasted, the welt attached and the inseam trimmed, it is customary, prior to attaching the outsole, to fill the cavity flush with the top of the inseam with a plastic filling material, such, for example, as a mixture of ground cork and a binder, which may or may not be thermoplastic and therefore require to be heated.

According to one feature of the present invention, the shoe is held stationary with the rim of the cavity (the top of the inseam in a welt shoe) pressed firmly against a plate, and filling material is forced into the space beneath the plate. In the illustrated machine a receptacle for filling material is located above the plate, there being a passageway leading from the bottom of the receptacle through the plate. The shoe is presented, bottom-side up, to the plate and clamped against the plate, and then filling material is forced from the receptacle through the passageway into the cavity in the bottom of the shoe.

With the construction described above, it is of course possible for the filling material to flow out from beneath the rear end of the plate through the gap which is present at that end; and, depending upon the nature of the plastic filling material it may be desirable to close this gap. To this end there is provided, in accordance with another feature of the invention, a dam which is brought down upon the bottom of the shoe to close this gap. In the illustrated construction this dam comprises a series of fingers which extend crosswise of the shoe and are yieldingly mounted so that when pressed against the bottom of the shoe they accommodate themselves to the cross-sectional profile of said bottom.

These and other features of the invention, including certain details of construction and combinations of parts, will be described as embodied in an illustrated machine and pointed out in the appended claims.

In the accompanying drawings:

Fig. 1 is a side elevation of a machine in which the invention is embodied, part of a supporting column thereof being broken away;

Fig. 2 is a view, in vertical section on the line II—II of Fig. 3, of a portion of the machine; and

Fig. 3 is a vertical section on the line III—III

of Fig. 2 showing the shoe bottom engaging fingers in engagement with a shoe bottom.

The illustrated bottom filling machine has a frame comprising a column 1 to the upper end 5 of which is secured a casting 3. Projecting upwardly from the casting 3 are two spaced rods, one of which (at the right of the machine) is shown at 5 in Fig. 1, the other of these rods being at the left side of the machine and positioned behind the rod 5, as seen in Fig. 1.

Secured to upper ends of the rods 5 and supported thereby is a plate 7. A lower surface 9 of this plate provides a shoe bottom engaging surface and lies in a generally horizontal plane. Since, however, the forepart portion of a shoe bottom usually is curved slightly convexly, both widthwise thereof and lengthwise thereof, it is usually desirable that the surface 9 of the plate 7 should not lie accurately in one plane but should be slightly curved concavely both widthwise and lengthwise to correspond to the curvature of the forepart of the shoe bottom to be operated upon. Mounted beneath the plate 7 is a shoe support in the form of a roll 11 of rubber or like resilient material. The roll 11, the axis of which is horizontal and extends widthwise of the plate 7, is supported on a stud 13 extending between upwardly extending plates, spaced widthwise of the machine, one plate being shown 15 at 15 in Figs. 1 and 2, the plates being secured to a block 17 threaded upon the upper end of a vertical plunger 19 which is slidable in a vertical bearing 21 in the casting 3. The plunger 19 extends below its bearing and its lower end is

forked. A horizontal stud 23, extending between the bifurcations of the lower end of the plunger, has a metal roll 25 rotatably mounted thereon. The roll 25 rides on the peripheral surface of a cam member 27 which is rotatably mounted on 20 a horizontal stud 29 fixed, vertically below the plunger, in a plate 31 secured to one side of the casting 3 and a narrower plate 33 secured to the other side of the casting 3. The cam member 27 has fixed thereto and extending outwardly 25 therefrom a hand lever 35 of substantial length also pivoted on the stud 29. The arrangement is such that an operator, by depressing the end of the hand lever remote from the cam member 27, may cause the cam member to be rotated in an anticlockwise direction as seen in Fig. 1 to cause the roll 25 to be raised, thereby causing the shoe supporting roll 11 to be raised. The roll 11 is normally in lowered position so that there is room for the insertion of the forepart of a shoe

50 S between the shoe supporting roll and the plate 55

7. The operator inserts the forepart of the shoe on its last 1 , bottom-side-up, between the roll 11 and the plate 7 with the toe end of the shoe against a gage 109 , and depresses the hand lever 35 , whereupon the roll 11 will be raised and the shoe gripped between the plate and the roll, this being the position of parts shown in Figs. 1 and 2. The hand lever 35 has a pawl 39 , pivotally mounted thereon which cooperates with teeth 41 formed on an arcuate edge on the plate 31 , the center of curvature of which is the axis of the stud 29 about which the hand lever pivots, a spring 45 being provided to urge said pawl into engagement with said teeth. The pawl 39 serves, when the shoe has been firmly gripped in position as aforesaid to lock the hand lever 35 in its position of pressure application so that the operator need not continue to exert pressure on the hand lever to maintain the shoe pressed against the plate 7 . The pawl 39 has a handle 47 projecting therefrom by operation of which the pawl may be released from the teeth 41 when it is desired to remove the shoe. The illustrated shoe is of the Goodyear welt type, the cavity to be filled lying within the inseam 37 which constitutes the wall of the cavity, and the top of which (assuming that the shoe is bottom-side-up) forms the rim of the cavity. In the positions of parts shown in Figs. 1 and 2, the shoe is securely held with the plate 7 pressed firmly against the top of the inseam. There is thus a space 39 between the forepart of the bottom of the insole and within the inseam; and it is into this space that the filling material is forced, as will appear below.

The plate 7 bears against the top surface of the wall 37 around the whole of the forepart of the shoe bottom. The shank portion of a shoe bottom is normally inclined at an angle to the forepart and if it is desired that the filling operation should extend some distance rearward of the junction between the forepart and the shank portion, the plate 7 may have a curved extension (not shown) shaped to bear against the said wall at this portion of the shank as well as round the forepart. Whether the shoe bottom cavity is to be filled at the forepart only or whether a shank portion is also to be filled, the said plate should bear firmly against the top of the wall or inseam 37 around the portion of the cavity to be filled and by so doing should serve to seal the cavity so as to prevent the bottom filling material, when extruded under pressure into the cavity, from passing beyond said wall. It will be realized that the said wall does not extend fully around the cavity to be filled since at the end of the cavity remote from the toe end of the shoe there will be a gap, extending transversely of the shoe between the plate 7 and the shoe bottom which is not closed by said wall. It is not necessary in all circumstances that this gap should be closed, since it has been found that, if the bottom filling material is extruded into the cavity 39 at or adjacent the toe end of the cavity, the material will flow adequately to fill the cavity up to said wall at the toe end and sides thereof before it travels rearward sufficiently far for it to begin to emerge through said gap. However, there is provided an arrangement, which will now be described, for closing at least the major part of said gap to prevent the bottom filling material exuding in substantial quantity through said gap before the cavity has been adequately filled.

This arrangement comprises a plurality of

spring-pressed fingers 51 which are mounted side by side in bearings in a thickened marginal portion 53 of the plate 7 extending across the shoe bottom at the locality of the said gap. The fingers 51 are held in position in the portion 53 by means of a plate 54 bolted to the portion 53 , each finger being capable of individual vertical sliding movement in the said bearings. The lower ends of these fingers are beveled at 55 so that each finger is adapted to engage the shoe bottom with more or less line contact. Each finger 51 has an enlarged upper end 57 which is engaged by a C-shaped spring 59 . The springs also bear against a rod 61 fixed in brackets 63 secured to the plate 7 , and each tends to urge its finger downwardly. The maximum downward movement of each finger 51 is limited by the engagement of its enlarged upper end 57 with the top of the bearings in which the fingers are slideable. The enlarged upper ends 57 of the fingers 51 are each vertically slotted at 64 , and a horizontal rod 65 passes through the slots 64 , the slots being of sufficient length to allow each finger 51 to have some vertical movement without movement of the rod. The rod 65 is normally held, by means hereinafter referred to, in an upward position and thereby holds the fingers 51 in raised positions so that when a shoe bottom is brought into engagement with the plate 7 the lower ends of the fingers do not at that time engage the shoe bottom. Means hereinafter described is provided by which the rod 65 is allowed to descend before the extruding operation fills the bottom cavity. The fingers descend under the action of their springs 59 so that their lower ends engage the shoe bottom along a line extending across the shoe bottom at the rear end of the cavity 39 to be filled and serve to close the gap aforesaid. Each finger will descend as far as it is permitted to do by the portion of the shoe bottom with which it contacts, and the individual fingers will take up different levels, as seen in Fig. 3, in accordance with the transverse curvature of the shoe bottom along the line of contact with the fingers thus closing the said gap, in the case of shoes of different sizes or shapes, more effectively than could be done by a single member.

The plate 7 has a member 66 projecting upwardly therefrom, this member being herein shown as formed integrally with the plate. In this member is formed a cylinder 67 , the axis of which is vertical. An aperture 69 is provided in the member 66 , which extends through the wall of the cylinder and enables a supply of bottom filling material to be introduced into the interior of the cylinder, for example, by means of a chute 70 . The cylinder 67 is open at its upper end, and movable in it is a piston 71 , the upper portion of which is pivotally connected to a hand lever 73 pivoted on a horizontal pivot 75 to an upwardly extending link 77 pivoted at its lower end to a lug 79 on the casting 3 . The hand lever 73 is normally held in a raised position by means of a spring 81 connected to a rearwardly extending arm 83 of the hand lever and to a hook 85 on the casting 3 . When the operator depresses this hand lever the piston is lowered in the cylinder. When the piston is at the upper part of its stroke it is located above the aperture 69 in the wall of the cylinder 67 so that filling material can be introduced into the cylinder below the piston. When the piston descends it passes below the said aperture and exerts pressure on the filling

material below it. The bottom of the cylinder is located a short distance above the lower surface 9 of the plate 7 but passages 87 lead from the bottom of the cylinder 67 through the plate 7 through which passages, when the piston is lowered in the cylinder, the filling material is extruded, and the extrusion under pressure of the filling material through them causes the filling material to enter the cavity and spread itself therein under pressure until it is pressed well up against the wall of the cavity within the inseam. Although the machine shown in the drawings is provided with a plurality of passages 87, it has been found that in most cases the desired effect can be obtained merely by providing one passage which is located near to the toe end of the cavity. The filling material extruded through a passage so positioned appears first to fill the toe end of the cavity up to the wall thereof and then travel rearwardly of the cavity, spreading to the cavity wall as it does so, until the desired filling has been effected.

It has been mentioned above that satisfactory results may be achieved in many cases even though the aforesaid gap between the plate and the shoe bottom at the rear end of the cavity is not closed. In such cases, assuming the filling material to be introduced at the toe portion of the cavity, the filling material appears to spread rearwardly in a front extending right across the width of the cavity so that as it travels it fills the cavity across its full width and does not emerge from said gap until the whole cavity has been filled.

If, however, gap-closing fingers as already referred to are provided, they serve to ensure that no premature escape of a substantial amount of filling material takes place at said gap before the cavity has been adequately filled. The rod 65 which passes through the slots 64 in the enlarged upper portions of the fingers 51 is supported by two links 91 (one at each side of the apparatus) from which link stems 93 project upwardly. Each stem 93 passes through an enlarged bore in a horizontal rod 97 secured to the hand lever 73 by a bolt 99. Above the horizontal rod 97 each stem 93 has two lock nuts 101 thereon. The arrangement is such that when the hand lever 73 is in its normal raised position the horizontal rod 97, by engagement with the nuts 101, holds the links 91 and therefore the fingers 51 in a raised position.

Immediately the hand lever 73 is depressed by the operator to cause the piston 71 to begin to effect an extruding operation, the links 91 are allowed to move downwardly, and the fingers 51 are permitted to descend to engage the shoe bottom and close the said gap. Conveniently, however, a gap 103 is provided between two adjacent fingers, the fingers being spaced apart on the rod 65 by means of a washer 105, so that the operator may determine when the filling operation has been completed as this will be indicated by observing when the filling material begins to exude through such gap 103.

If the particular filling material employed is of the kind requiring heat to bring it into spreadable condition, the plate 7 and the member 66 in which the cylinder 67 is formed will be maintained at the desired temperature by means of electric heating cartridges 107 provided in the member 66.

Having thus described our invention, what we claim as new and desire to secure by Letters Patent of the United States is:

1. A machine for operating upon a welt shoe to fill the cavity in the bottom thereof which is bounded, except at the rear, by the inseam, said machine comprising a stationary plate, a support adapted to engage the toe portion of the shoe, means for causing the support to press the inseam into firm contact with the plate, said plate having passing through it an opening the cross-section of which is small compared to the area of the cavity in the bottom of the shoe, a receptacle for filling material, said receptacle being carried by the plate and communicating at all times with the opening, and means for forcing filling material from the receptacle through the opening and beneath the plate and causing it to flow over the surface of the insole of the shoe and in so flowing to spread to the extent permitted by the inseam.
2. A machine for filling the cavity in the bottom of a shoe, said machine having in combination a plate, means for holding the plate firmly against the rim of the cavity, a receptacle for filling material, means for forcing filling material into the cavity beneath the plate, and means movable with respect to the plate into contact with the bottom of the shoe for preventing filling material from flowing out from beneath the plate.
3. A machine for filling the cavity in the bottom of a shoe, said machine having in combination a plate, means for holding the plate firmly against the rim of the cavity, a receptacle for filling material, means for forcing filling material into the cavity beneath the plate, a dam movable with respect to the plate and adapted to extend crosswise of the bottom of the shoe, and means for moving said dam into contact with the bottom of the shoe to limit the flow of filling material toward the rear end of the shoe.
4. A machine for filling the cavity in the bottom of a shoe, said machine having in combination a plate, means for holding the plate firmly against the rim of the cavity, a receptacle for filling material, means for forcing filling material into the cavity beneath the plate, a dam of independently yieldable sections adapted to extend crosswise of the bottom of the shoe, and means for moving said dam into contact with the bottom of the shoe to limit the flow of filling material toward the rear end of the shoe.
5. A machine for filling the cavity in the bottom of a welt shoe, said machine having in combination a receptacle for filling material, a plate, a support for engaging the toe portion of a shoe, means for causing the support to press the inseam of the shoe firmly into contact with the plate, there being in the plate a passageway leading from the receptacle into the cavity beneath the plate, and means for forcing filling material through the passageway and for causing it to flow beneath the plate into contact with the inseam.
6. A machine for filling the cavity in the bottom of a shoe, said machine having in combination a plate, means for holding the plate firmly against the rim of the cavity, a receptacle for filling material, a normally inoperative dam which extends crosswise of the shoe, and means for moving said dam into contact with the bottom of the shoe so as to limit the flow of filling material toward the rear end of the shoe and for forcing filling material from the receptacle into the space between the plate and the bottom of the shoe.
7. A machine for filling the cavity in the bottom of a shoe, said machine having in combina-

tion a plate, means for holding the plate firmly against the rim of the cavity, a receptacle for filling material, a normally inoperative dam which extends crosswise of the shoe, and a single member actuation of which moves the dam into operative position in contact with the bottom of the shoe and forces filling material into the cavity.

8. A machine for filling the cavity in the bottom of a shoe, said machine having in combination a plate, a receptacle for filling material located above the plate, there being a passageway leading from the receptacle through the plate, a

toe gage for facilitating the proper presentation of a shoe bottom-side-up to the plate, means for forcing the shoe toward the plate and for holding the rim of the cavity firmly against the plate, a normally inoperative dam extending crosswise of the shoe near the rear end of the plate, said dam comprising a plurality of yieldingly mounted fingers, and means for pressing the fingers yieldingly against the bottom of the shoe and for forcing filling material from the receptacle through the plate into the cavity.
